UNITED STATES PATENT OFFICE

FRANCES E. SWANSTROM, OF DULUTH, MINNESOTA

GARMENT

Application filed August 30, 1928. Serial No. 302,924.

This invention relates to garments and has special reference to an overall garment particularly adapted for use by children, though deemed equally efficient for adults.

5 The principal object is to produce a garment of this type having a fastening attachment of novel construction which will permit of putting the complete garment and attachments through a wringer or mangle during 10 the process of cleaning and pressing.

Another object is to produce a garment of this character requiring as few and simple fastening attachments as possible;

15 Another more specific object is to produce a novel form of fastening attachment which will permit of passing through a wringer or the like.

Other objects and advantages of the invention will appear in the further description 20 thereof.

Referring now to the accompanying drawing, forming part of this application, and wherein like reference characters indicate like parts:

25 Figure 1 is a front elevation of a garment embodying the invention;

Figure 2 is a rear elevation.

As is obvious, the body portion may or may not have arms attached thereto, and if attached they may be of any desired length, and also the legs may be of any desired length.

1 and 2, represent the overlapping flaps of the front of the body portion, while 3 represents the back of the body portion. 4 indicates the legs which terminate upwardly in front in the flaps 1 and 2, or at least are integral therewith, and in the back terminate in the seat flap 5, said flap being free except 35 as it is held by the belt sections 6 and 7 from a point at either side, indicated at 8, which is in a plane with the lower extremity of the back portion 3, such extremity being indicated by the dotted line 9 in Figure 2, the 40 seat flap being formed abnormally full for 45

the comfort of the wearer and convenience in adjustment.

The belt sections 6 and 7 which are attached to the upper corners of the flap 5 are relatively short, the former being provided with the vertically elongated slot or opening 10, while the latter is provided with the arrowhead shaped fastening member 11. This fastening member 11 is for engagement within the elongated slot or buttonhole 12 in the flap 1 of the front of the garment. A similarly shaped arrowhead fastening member 13 is permanently attached to the apex of the flap 2 and extendible through the buttonhole 14 at the base of the flap 1 similar to the buttonhole 12, and when thus extended is cooperatively engageable with the belt section 6 having the buttonhole 10 therein.

50 By this means there is provided a belt section of substantially equal length upon either side of the flap portion, thus avoiding the annoyance of a long belt section which is sometimes employed in similarly shaped garments, and having no attachments of any considerable length at least to either of the 55 overlapping flaps in the front of the garment. For convenience in holding the belt sections to the body portion there is provided a loop 15 attached to the back of the body portion adjacent the upper corner of the seat flap 70 when in closed position, and through which the belt sections may be threaded, as clearly seen in the drawings.

75 From the above it is evident that I have provided an exceedingly simple and practical garment, and one requiring no other fastening means either in the front above the crotch where buttons are usually employed, or about the neck, as it is evident that the use of a necktie for example would act as an ample 80 additional holding means about the upper part thereof, and that the seat flap is most readily adjusted simultaneously with the opening of the front flaps.

85 Having thus described my invention, what 90

I claim and desire to secure by Leter Patent,
is:

5 The combination with a garment of the
class described having body and leg portions,
of integral overlapping flaps comprising the
entire front of the body portion, a seat flap
overlapping the entire lower portion of the
back of the body portion, and fastening
means attached to the upper opposite corners
10 of the seat flap, one for cooperative engage-
ment with one front flap through the gar-
ment, and the other for cooperative engage-
ment with the other front flap externally of
the garment.

15 15 In testimony whereof I affix my signature.
FRANCES E. SWANSTROM.
